(57) **CLAIM**

The ornamental design for an outdoor luminaire, as shown and described.

DESCRIPTION

FIG. 1 is a perspective view of a first embodiment of the outdoor luminaire of the present design;

FIG. 2 is a front elevation view thereof;

FIG. 3 is a rear elevation view thereof;

FIG. 4 is a right side elevation view thereof, the left side elevation view being a mirror image thereof;

FIG. 5 is top plan view thereof;

FIG. 6 is a bottom plan view thereof;

FIG. 7 is a perspective view of a second embodiment of the outdoor luminaire of the present design;

FIG. 8 is a front elevation view thereof;

FIG. 9 is a rear elevation view thereof;

FIG. 10 is a right side elevation view thereof; the left side elevation view being a mirror image thereof;

FIG. 11 is a top plan view;

FIG. 12 is a bottom plan view;

FIG. 13 is a right side elevation view of a third embodiment of the outdoor luminaire of the present design, the left side elevation view being identical thereto;

FIG. 14 is a front elevation view thereof; the rear elevation view being identical thereto;

FIG. 15 is top plan view thereof;

FIG. 16 is a bottom plan view thereof;

FIG. 17 is a perspective view thereof;

FIG. 18 is a right side elevation view of a fourth embodiment of the outdoor luminaire of the present design, the left side elevation view being identical thereto;

FIG. 19 is a front elevation view thereof; the rear elevation view being identical thereto;

FIG. 20 is a top plan view thereof;

FIG. 21 is a bottom plan view thereof; and,

FIG. 22 is a perspective view thereof.

The broken lines in the figures illustrate environmental structure or portions of the outdoor luminaire that are not claimed.
